UNITED STATES PATENT OFFICE.

GUMBY S. BLUM, JR., AND JOSEPH A. PHILLIPS, OF BALTIMORE, MARYLAND.

BUTTON.

SPECIFICATION forming part of Letters Patent No. 377,446, dated February 7, 1888.

Application filed September 14, 1887. Serial No. 249,674. (No model.)

To all whom it may concern:

Be it known that we, GUMBY S. BLUM, Jr., and JOSEPH A. PHILLIPS, citizens of the United States, residing at Baltimore, in the 5 State of Maryland, have invented certain new and useful Improvements in Buttons; and we do hereby declare the following to be a full, clear, and exact description of the invention, such as will enable others skilled in the art to 10 which it appertains to make and use the same.

This invention relates to certain improvements in buttons, and it has reference more particularly to buttons of that class in which two metallic disks, one provided with a cross-bar and the other with a hub and central opening, comprise the essential parts of the button. In buttons of this description previously constructed the thread holding the button to the garment was considerably chafed 15 and cut by coming in contact with the sharp interior edge of that portion of the rear disk forming the central opening, which has usually been turned directly toward the bar and almost surrounds the thread. Furthermore, 20 these buttons have been somewhat objectionable, for the reason that the cross-bar as hitherto formed has not been of such strength as to withstand any considerable amount of strain.

The object of our invention is to overcome 30 these and other objectionable features; and to this end it comprises a button in which the inner edge of the opening or hub of the rear disk is turned outwardly from the center and toward or upon itself, in which the cross-bar of 35 the front plate is considerably strengthened by the peculiar conformation given it, and in which other features are embodied, that will be hereinafter referred to, and pointed out in the claims.

40 In the accompanying drawings, wherein similar letters of reference indicate like parts, Figure 1 is an enlarged top or plan view of our improved button; Fig. 2, a cross-section of the same on line $x-x$ of Fig. 1, and Fig. 3 a 45 cross-section on line $y-y$ of Fig. 1.

Referring to the drawings, A represents the front disk or plate, having the cross-bar a , over which the thread is passed, formed integral therewith. This disk may be of ornamental 50 brass or other suitable metal, and is preferably curved, as shown in Fig. 2, to give added flexi-

bility and strength, and at the same time present a smooth and rounded exterior. It will be noticed that the cross-bar a is depressed at its central portion, forming, in connection 55 with the front disk, a sinuous convex curve. By this construction the strain upon the cross-bar a is directly in line with the texture of the metal, and is not exerted in an angular direction. At its junctions with the disk A the 60 bar a is preferably made slightly wider, forming the rounded corners e . This prevents the metal from splitting, and gives the cross-bar added strength at the point where it is ordinarily weakest. By reason of this depressed 65 portion of the bar the thread is further kept in line with the center of the button, and is consequently prevented from being chafed by the edges of the front disk.

B, Figs. 2 and 3, shows the rear disk, held 70 in place by the overlapping edges of the front disk, A, in the usual manner. The edge of the hub b of this disk is turned inwardly and upon itself in order to form the circular flange b' , having its edges turned back toward the wall 75 of hub b , so as to present a flaring and perfectly smooth and rounded eyelet-shaped opening. The edge of the flange b' before being subjected to the turning-in operation is slightly countersunk, as shown at c , in order to thin 80 out the metal at this point and insure its uniform expansion. In some cases, however, we may turn up and finish this portion of the hub against an interior die or former.

Fig. 3 is a cross-sectional view of the button 85 on line $y-y$ of Fig. 1, showing the ears formed in punching the front disk turned under the cross-bar to strengthen it at its central depressed portion, and showing, also, the rounded and gradually-widening shape of the cross-bar 90 at its junction with the front disk, A. It will thus be seen that our button will not only withstand a very considerable strain upon the cross-bar, but offers a rigid and extremely smooth hub that is devoid of any sharp edges 95 and cannot abrade or otherwise injure the retaining-thread or the garment to which it is attached. Furthermore, by virtue of the shape given to the front disk and bar, a greater degree of flexibility and strength is imparted to 100 it, and the button is more readily inserted in and removed from the button-hole.

Having now described our invention, what we claim as new, and desire to secure by Letters Patent, is—

1. As an improved article of manufacture, a button of the class described, having the central portion of its back plate or disk perforated and turned upward and outward within the interior of the button, so as to form a smooth eyelet-shaped passage for the retaining-thread, substantially as set forth.
2. A button comprising, substantially, a front disk or shell, having a bar or other thread-support formed integral therewith, and a rear disk

or shell provided with a hub and central opening, the metal forming the lower edge of said hub being countersunk and turned upward and outward within the interior of the button, substantially as and for the purpose set forth.

In testimony whereof we affix our signatures in presence of two witnesses.

GUMBY S. BLUM, JR.
JOSEPH A. PHILLIPS.
